UNITED STATES PATENT OFFICE.

DENNIS E. CROWLEY, OF MILWAUKEE, WISCONSIN.

ANTICREEPING DEVICE FOR RAILS.

1,227,755.

Specification of Letters Patent. Patented May 29, 1917.

Application filed August 19, 1916. Serial No. 115,742.

To all whom it may concern:

Be it known that I, DENNIS E. CROWLEY, a citizen of the United States, and resident of Milwaukee, in the county of Milwaukee and State of Wisconsin, have invented certain new and useful Improvements in Anti-creeping Devices for Rails; and I do hereby declare that the following is a full, clear, and exact description thereof.

10 The present invention relates to new and useful improvements in anti-creeping devices for railway rails, more particularly of that type including a portion adapted to grip a rail laterally of a tie, and a portion connected with the first portion and abutting the tie.

It is in general the object of the invention to simplify and otherwise improve the structure of devices of this character, and to improve their efficiency.

A more specific object resides in the provision of such a device which may be assembled in a most ready and convenient manner, and which, when assembled, has its parts so disposed that a casual inspection of the device by a person walking along the track, will disclose whether or not the parts of the device are in operative relation to the rail, in contradistinction to those types of devices 30 wherein the tie-abutting member is disposed under the rail, or otherwise concealed.

It is further the object of the invention to utilize to a maximum extent the twisting binding action of a rail embracing member 35 held at one end, whereby tendency to creeping of the rail will result in a more tight engagement of the anti-creeping device therewith.

With the above and other objects and advantages in view, the invention resides more particularly in the novel combination, arrangement and formation of parts more particularly hereinafter described and particularly pointed out in the appended claim.

45 In the drawings—

Figure 1 is a plan view of the improved anti-creeping device associated with a railway rail and tie, the ball portion of the rail being broken away.

50 Fig. 2 is a transverse sectional view on the line 2—2 of Fig. 1.

Referring now more particularly to the accompanying drawings, 5 designates a railway tie on which is transversely disposed a conventional rail 6. The tie abutting member of the improved anti-creeping device

comprises an elongated block 7 provided in one side with a longitudinal channel 8 receiving one side of the base flange of a rail, and at its end adjacent the tie 5, the block is 60 provided with a depending abutting shoe 9 which is extended under the rail base flange, and inwardly of the said grooved side of the block 7. The outer side of this block 7 is 65 inclined outwardly toward the shoe 9, whereby a wedge-shape is imparted to the block, and the upper portion of this inclined outer side is beveled as at 10 for a purpose later to be described. The rail-gripping member of the device comprises a bar 11 extending transversely under the base flange of the rail, and its end farthest from the wedge block is directed upwardly and inwardly to form a channel 12 receiving the adjacent side of the rail base flange, while its end 70 adjacent the wedge block is directed upwardly to engage said block and provided with an inwardly extending beveled portion 13 fitting against the beveled portion 10 of the wedge block.

With the parts assembled as described, the bar 11 is driven inwardly on the wedge block to tightly bind the rail between said block and the channeled portion 12 of the bar, and thus tendency to creeping of the rail, 75 in the direction indicated by the arrow in Fig. 1, will be resisted by abutment of the shoe 9 of the wedge block with the tie. It is further noted that this tendency to creeping will tend to move the channeled end 12 80 of the bar with the rail, and thus procure a twisting of the bar on the immovable wedge block 7, to thus increase the binding action exerted, this operation being procured more readily by reason of the loose connection of 85 the bar with the wedge block.

In assembling the device with relation to a rail, the wedge block 7 is first applied to one side of the rail, and the bar 11 then disposed under the rail and engaged as described with the block and rail base flange, it being noted that the distance between the inwardly directed turned end portions of the bar is greater than the width of the rail base flange.

Thus an exceedingly simple, highly efficient and readily assembled anti-creeping device has been provided, comprising only two parts, which are susceptible of ready manufacture.

Inasmuch as the tie-abutting wedge block 7 is disposed at the side of the rail, a per-

son walking along the track, can by a most casual inspection ascertain the relation of the parts to the rail, to determine their operation.

5. What is claimed is:

An anticreeping device for rails comprising a bar having one end portion formed to embrace one side of the base flange of a rail, the other end portion of the bar being directed upwardly to form a flat bearing face at its inner side disposed at a right angle to the plane of the bar, said other end portion being directed inwardly at its free

extremity to form an inclined flat bearing face, a tie abutting wedge shaped block 15 having one side grooved to receive the base flange of a rail and its other side formed to provide bearing faces corresponding to the bearing faces of the bar, and said bar having its adjacent portion cut away to receive the lower portion of the wedge block. 20

In testimony that I claim the foregoing I have hereunto set my hand at Milwaukee, in the county of Milwaukee and State of Wisconsin.

DENNIS E. CROWLEY.
